M. GUSTIN.

SLIPPER.

APPLICATION FILED APR. 6, 1917.

1,265,774.

Patented May 14, 1918.

Max Gustin Inventor

By his Attorney

Yours sincerely,

UNITED STATES PATENT OFFICE.

MAX GUSTIN, OF NEW YORK, N. Y.

SLIPPER.

1,265,774.

Specification of Letters Patent. Patented May 14, 1918.

Application filed April 6, 1917. Serial No. 180,086.

To all whom it may concern:

Be it known that I, MAX GUSTIN, a citizen of the United States, and a resident of New York city, in the county of New York and State of New York, have invented certain new and useful Improvements in Slippers, of which the following is a specification.

This invention relates in general to boudoir or toilet slippers, and particularly to certain improvements in the sole and heel of such slippers, which adapt the latter specially to be sold in combined form to have any desired upper or vamp attached thereto by the purchaser.

15 The object of my invention is to provide means on a sole of the nature described, which shall permit of the applying of an upper thereto without causing the soft portion of the inner sole to be drawn toward the sides of the upper, thus giving the completed slipper a smooth and neat inside finish.

Another object of my invention is to provide a sole of the nature described which 25 shall always keep the shape best calculated therefor for the use thereof in combination with a heel to form the supporting member of a slipper.

A further object of my invention is to 30 provide a sole and heel which shall easily accommodate themselves to the shape of the wearer's foot and not slip forward under the pressure exerted thereby.

A still further object of my invention is 35 to provide a heel and sole, cheap to manufacture and adapted to form a neat and comfortable slipper when the upper is attached thereto.

The various further objects and advantages will more fully appear from the detailed description and the features of novelty will be particularly pointed out in the claims.

In the drawings accompanying this specification,

Figure 1 is a longitudinal section of my improved sole and heel.

Fig. 2 is a plan view thereof.

Fig. 3 is a sectional view taken along line 50 3-3 of Fig. 1.

Fig. 4 is a part sectional view taken along line 4-4 of Fig. 1.

Fig. 5 is an elevational view of a modified form of my invention, and

55 Fig. 6 is a plan view of another modification.

Referring in detail to the drawing, my improved sole is made up of a bottom layer 10 preferably of leather, a similarly shaped layer 11 or paste-board or the like material superposed thereon and cemented or otherwise suitably attached thereto. A suitable binding 12 is applied, preferably by stitches, along the edges of this last layer to form a neat border 13, along which any desired upper may be attached.

The inner sole consists of a neat padded cushion 14 of similar shape to that of the outer layers 10 and 11, and of size such that it covers the surface of the layer 11 only up to the inner edge of the border 13, thus leaving the latter exposed and free to receive the attaching means for the upper. It is, therefore, clear that when the upper is attached, the inner sole is not at all disturbed, 75 the necessary stitches being taken through the bordered edges of the paste-board layer. Consequently, after the upper is applied, the slipper presents a neat and smooth inside finish, no portion of the inner sole being 80 drawn toward the walls of the upper, while the soft cushion affords great comfort to the wearer. The upper, furthermore, cannot be torn away from the sole by the setting of the foot into the slipper, especially should 85 the foot be of somewhat greater width than the slipper, as is the case in present constructions where the upper is stitched directly to the soft part of the inner sole.

The construction of the inner sole will 90 now be described in detail. As will be clear from the drawing, the cushion is made up of a bottom layer 15 preferably of the same material as the layer 11, and of size and shape to correspond to the surface there- 95 of bounded by the border. Several layers 16 of cotton, wool or felt or the like soft padding material, are superposed on this layer 15, and these are covered over and held to the latter by a piece 17 of muslin or 100 satin or any other like material preferably of the same color as the binding 12, and which is drawn around the bottom of the layer 15 to be there cemented or otherwise attached thereto as at 18.

To maintain the inner and outer soles in their proper shape and to provide support to the wearer's foot, I provide a stiff shank 19 which is embedded in the shaped fiber-board 20. In the form shown in the drawing, the shank member is superposed on the layer 15 beneath the padding of the cushion.

The improved heel 21 comprises a block of wood 22 of suitable size and shape and having a strip of leather 23 attached at the bottom thereof. To give the slipper a neat appearance, I preferably provide the heel with a covering 24 of like material and color as 17 of the cushion. The heel is further recessed at the top as at 25, so that the heel portions of the layers of the inner sole may be countersunk therein so that the bottom edge of the cushion is flush with the face of the border 13 throughout its whole periphery. As will be clear from the drawing, the top of the heel and the recess thereon, 15 are made on a bias, so that when the inner sole is attached thereto, the heel or rear portion thereof slants downward. This bias given to the sole at the heel portion thereof is extremely advantageous in that it prevents the pressure of the wearer's foot from causing the heel to rotate about the lower base edge thereof and thus force the slipper to slip forward, a difficulty which has hitherto been encountered in most slippers of 20 the kind herein described.

In the practice of my invention, I preferably put together the leather layer 10, the paste-board layer 11, the smaller paste-board layer 15 and the shaped fiber-board 20, and set them into the recessed portion of the heel. I then drive several small nails 26 therethrough, making the holes 27. The nails together with the layers of the inner sole are then pulled out of the heel, and several small pieces of leather 27' are cemented over the heads of the nails, to keep the nails from being forced up, and to prevent discomfort to the wearer. To help hold the layers together, I apply coatings of 30 cement therebetween. I then place the several layers of padding in position, and complete the cushion by applying the covering 17 as already described. The inner sole is now turned over wrong side up with the 35 nails sticking up, and the heel is fitted on by means of the holes 27 already made therein. A slight hammering then securely fastens the heel to the sole. Of course, cement may also be applied between the top surface 40 of the heel and the bottom surface of the rear of the inner sole.

In the modification shown in Fig. 5, I show an embodiment of my invention adapted to a more expensive workmanship of boudoir or toilet slippers in which the heel portion of the lower leather sole does not rest on the top of the heel underneath the rear of the inner sole, but passes around the front face of the heel as at 28 and thence 45 underneath the wooden block between the bottom thereof and the leather strip, as shown at 29.

In a still further modified form of my invention shown in Fig. 6, I have shown an adaptation thereof to the style of slippers 65 known to the trade as "mule" slippers for boudoir wear. In slippers of this kind, the upper is not made to extend over the whole sole, but only up to the instep adjacent the heel portion. The border 13 is, therefore, 70 made to taper as at 30 until it thins down to the edge of the paste-board layer 11, as shown at 31.

Many variations may of course be resorted to without departing from the scope of my 75 invention.

Having thus described my invention, I claim as new and desire to secure by Letters Patent:—

1. As an article of manufacture the combined sole and heel of a slipper, said sole comprising an outer molded layer, a similarly shaped layer superposed thereon, a binding applied along the edges of said last mentioned layer to form a border of 85 an outline corresponding to the outline of the sole and heel, and a cushion on said sole, said cushion comprising a bottom molded layer of lesser length and width than the sole, a molded layer having a shank embedded therein superposed on said bottom layer, layers of padding material disposed on said bottom and shank layers, and covering means extending over said padding layers and secured underneath said bottom 90 layer, said cushion being disposed within the inner edge of said border and upstanding therefrom, the border being thus left free to have an upper attached thereto.

2. As an article of manufacture the combined sole and heel of a slipper, said sole comprising an outer molded layer, a similarly shaped layer superposed thereon, a binding applied along the edges of said last mentioned layer to form a border of an outline of 100 the sole and heel, and a cushion on said sole, said cushion comprising a bottom molded layer of lesser length and width than the sole, layers of padding material disposed on said bottom layer, and covering means extending over said padding layers, said cushion being disposed within the inner edge of said border and upstanding therefrom the border being thus left free to have an upper attached thereto.

Signed at New York city, in the county of New York and State of New York, this 4th day of April, A. D. 1917.

MAX GUSTIN.
